[57] CLAIM

The ornamental design for a shirt hanger or similar article, substantially as shown.

DESCRIPTION

FIG. 1 is a front elevational view of shirt hanger or similar article showing my new design;

FIG. 2 is a rear elevational view thereof;

FIG. 3 is a side elevational view taken from the right of FIG. 1;

FIG. 4 is a bottom plan view thereof;

FIG. 5 is a top plan view thereof.
